UNITED STATES PATENT OFFICE

GEORGE H. GLADE, JR., OF CHICAGO, ILLINOIS

LAMP SOCKET

Application filed July 18, 1927. Serial No. 206,514.

This invention relates to an electric socket. It has for one object, to provide a socket which is substantially unbreakable. Another object is to provide a socket which may be assembled by hand without the use of tools. Another object is to provide a socket in which tension cannot come upon the individual wires so that undue strain does not fall upon them when the light is in use or carried about from place to place. Another object is to provide in a socket of the type described, means for readily fastening a clamping and guarding device to the exterior of the socket. Other objects will appear from time to time throughout the specification and claims.

This invention is illustrated more or less diagrammatically in the accompanying drawings, wherein:

Figure 1 is a side elevation with parts broken away.

Figure 2 is a longitudinal cross-section on an enlarged scale.

Figure 3 is a transverse cross-section taken on a line 3-3 of Figure 2.

Figure 4 is a similar transverse cross-section taken on line 4-4 of Figure 2.

Figure 5 is a partial longitudinal cross-section taken on line 5-5 of Figure 4.

Figure 6 is a view generally similar to Figure 2 with parts omitted and showing a modified form.

Figure 7 is a perspective view of the adjustable end wall or plug.

Like parts are designated by like characters throughout.

A is a tubular member which in the form here shown serves both as the container for the socket and wiring parts, and for the insulator. It is provided on its exterior with a relatively small annular groove A¹ and a larger groove A². A⁷ is a shoulder. Within the tube a pair of channels A³, A⁸ are provided. These terminate in shoulders A⁴. There are thus left between the channels A³, slightly raised portions or lands A⁵. Adjacent one end of the tube is the internal annular groove or depression A⁶.

B is a socket member provided with the relatively enlarged end portion B¹ and car-

rying a socket portion B². As shown especially in Figures 3 and 4, the member B, B¹ is provided with cut-away portions B³ in its sides, within which wiring connections B⁴ are positioned. The portions of the members B, B² and the shape and arrangement of the cut-away portions B³ is such that the raised portions A⁵ of the tube A fit into the cut-away portions B³ of the member B and thus preventing lateral twisting or rotation of this part.

C is a plug adapted to fit within one end of the tube A and to lie close to the groove or depression A⁶. C¹ is a spring ring which is fitted into the groove or depression A⁶; 65 when the plug C is in position and when so assembled, the plug is held against accidental outward displacement. C² is a central perforation in the plug C through which the lighting cable or conduit C³ may penetrate.

D, D are clamping parts adapted to be held together by screws D¹, D¹. They are fitted about the inner end of the cable C³ so as to grip it tightly. The clamp or 75 abutment D normally bears against the inner face of the plug C and thus when the lamp is carried by the cable, as frequently happens, any strain which comes upon the cable either through the weight of the lamp itself, or for any other reason, is carried, not by the inner conducting member C⁴, nor by small set screws B⁴ which fasten it to the socket but by the cable and cable casing C³ as a whole, clamped by the clamp D, D 80 which bears against the inner face of the plug screw.

E is a spring ring adapted to fit into the groove or depression A¹. About it a base F may be positioned as shown particularly 90 in Figures 1 and 2. This base embraces the outer end of the tube A and engages the ring E. The base F may carry as here shown, a cage F¹ which serves as a protection for the light.

G is a gripping part assembly held in the depression A² by a screw, G¹. This gripping part may be attached to a clamp and handle or other part by means of which the light may be used, positioned or adjusted. 100

The details of this apparatus form no part of the present invention and are therefore not shown in detail.

- 5 The interior diameter of the tube A is preferably provided with, or formed so as to have two dimensions. This appears particularly in Figure 5, the channels A³ being formed in the smaller part of the tube.
- 10 There is shown in Figure 6, a modified form in which the interior of the tube A is threaded. A threaded plug H is provided to close the end of the tube A and to hold the parts in position. It has a hole 15 H¹ which is preferably located centrally and may also be provided with a slot H² for a screw-driver or other tool by means of which it is screwed into or out of position. By thus providing the socket container or 20 tube A with a screw-threaded plug or end wall, said wall or plug may be adjusted longitudinally of the tube so as to positively engage the clamp D and position the same within the tube in a manner such as to 25 relieve the conductor of tensional strains and to prevent longitudinal movement of the socket within the tube.

It will be realized that whereas I have described and shown particularly an operative device, nevertheless many changes might be made in size, shape, number and disposition of parts without departing from the spirit of my invention. I, therefore, wish my description and drawings to be 35 taken in a sense diagrammatic.

I claim:

1. In combination in an electric light socket, a socket part provided with means for receiving the base of an electric lamp, 40 and also provided with means to which conductors from a power source may be attached, a combined insulating and handle member surrounding the socket part and shaped to conform thereto, the socket and 45 handle being provided with interfitting parts to prevent relative rotation, a removable closure plug for the handle member, a conduit extending into the handle through the plug and containing conductors the ends of 50 which are attached to the socket member, an abutment carried by the conduit between the plug and socket member, and means for adjusting the plug longitudinally of the handle into engagement with the abutment to position the abutment within the handle to prevent longitudinal movement of the socket member.

2. In combination in an electric light socket, a socket part and a containing part 55 enclosing said socket part and having an open rear end, an adjustable closure for said containing part, a conduit extending within the containing part and containing a conductor adapted to be attached to said socket member, and an abutment removably at-

tached about said conductor to be engaged and operatively positioned within the containing part by said adjustable closure member.

3. In combination, an electric light socket, 70 a containing part enclosing the socket, a conduit extending within the containing part and including conductors to be attached to the socket, and an abutment removably attached to the conduit adjacent to the socket member, the socket containing part including a movable end wall adjustably mounted therein and movable into engagement with the abutment to operatively position the same within the socket container. 75

4. In combination, an electric light socket, 80 a containing part enclosing the socket, a conduit extending within the containing part and including conductors to be attached to the socket, and an abutment removably attached to the conduit adjacent to the socket member, the socket containing part including a movable end wall, cooperative means between the end wall and the socket containing part permitting relative longitudinal adjustment of the end wall therein, whereby 85 to move the end wall into engagement with the abutment.

5. In combination, an electric light socket, 90 an insulating handle enclosing the socket, 95 the handle including an adjustable end wall, a conduit extending within the handle through the end wall and containing conductors attached to the socket, an abutment removably secured to the conduit between 100 the end wall and socket, the end wall and handle being co-operatively screw-threaded to permit relative adjustment thereof whereby the end wall may be moved into engagement with the abutment to operatively position the same with respect to the socket. 105

Signed at Chicago, county of Cook and State of Illinois, this 14th day of July, 1927.
